UNITED STATES PATENT OFFICE.

HENRY O. SCHMIDT, OF NEW BRITAIN, CONNECTICUT, ASSIGNOR TO TIFFANY STUDIOS, OF NEW YORK, N. Y., A CORPORATION OF NEW YORK.

DESIGN FOR A GLASS PANEL FOR LAMP-SHADES OR SIMILAR ARTICLES.

43,582.

Specification for Design.

Patented Feb. 18, 1913.

Application filed January 10, 1913. Serial No. 741,333. Term of patent 14 years.

To all whom it may concern:

Be it known that I, HENRY O. SCHMIDT, a citizen of the United States, residing at New Britain, in the county of Hartford and State of Connecticut, have invented a new, original, and ornamental Design for Glass Panels for Lamp-Shades or Similar Articles, of which the following is a specification, reference being had to the accompanying drawing, forming part thereof.

Figure 1 is a front elevation of my glass

panel for lamp shade or similar article. Fig. 2 is a plan view of the same. Fig. 3 is an end view of the same.

I claim:

The ornamental design for a glass panel for lamp shade or similar articles, as shown.

HENRY O. SCHMIDT.

Witnesses:

SHEFFIELD H. CLARKE,
ROGER W. EDWARDS.
